CLAIM

The ornamental design for the mounting device for a video camera, as shown and described.

DESCRIPTION

FIG. 1 is a perspective view of a mounting device for a video camera showing our new design;

FIG. 2 is a second perspective view of thereof;

FIG. 3 is a third perspective view thereof presented in an exploded view;

FIG. 4 is a fourth perspective view thereof presented in an exploded view;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof; and

FIG. 10 is a right side elevation view thereof.

FIG. 11 is a perspective view of a mounting device for a video camera showing a second embodiment of our new design;

FIG. 12 is a second perspective view of thereof;

FIG. 13 is a third perspective view thereof presented in an exploded view;

FIG. 14 is a fourth perspective view thereof presented in an exploded view;

FIG. 15 is a front elevation view thereof;

FIG. 16 is a rear elevation view thereof;

FIG. 17 is a top plan view thereof;

FIG. 18 is a bottom plan view thereof;

FIG. 19 is a left side elevation view thereof; and,

FIG. 20 is a right side elevation view thereof.

Broken lines shown in the drawings depict environmental subject matter and form no part of the claimed design.
